United States Patent Office

Des. 207,684
Patented May 16, 1967

207,684

PILL TRAY

Harry C. Welch, Sr., 1521 Avolancia Ave.,
Fullerton, Calif. 92132

Filed Mar. 8, 1966, Ser. No. 1,358

Term of patent 7 years

(Cl. D83—1)

FIG. 1.

FIG. 2.

FIG. 3.

FIG. 4.

FIG. 5.

FIG. 1 is a top plan view of a pill tray showing my new design thereof;

FIG. 2 is a front edge elevational view thereof, the rear elevational view thereof being symmetrically identical;

FIG. 3 is a bottom plan view thereof;

FIG. 4 is a right end elevational view thereof; and

FIG. 5 is a left end elevational view thereof.

I claim:

The ornamental design for a pill tray, substantially as shown and described.
